UNITED STATES PATENT OFFICE

2,045,363

UPHOLSTERY MAKING APPARATUS

Allister S. Mitchell, Detroit, Mich., assignor to
 National Automotive Fibres, Inc., Detroit,
 Mich., a corporation of Delaware

Application November 25, 1932, Serial No. 644,357

37 Claims. (Cl. 112—2)

This invention relates particularly to a machine for manufacturing stuffed, pleated upholstery. Such a machine is adapted, for example, to the manufacture of automobile seat-cushions, back-cushions, etc.

The primary object is to provide an improved machine and an improved method which will greatly facilitate the manufacture of stuffed, pleated upholstery.

10 More especially, the present invention is intended to provide a machine particularly suited to the use of pre-cut covers in forming cushions, for example, for automobiles.

A further object of the invention is to provide a machine having endless conveyor-members 15 for advancing the pre-cut cover fabrics to sewing mechanisms and forming therein seam-portions and intervening pleat-fullnesses. In a preferred embodiment of the invention, this is 20 accomplished by arranging the conveyors to converge towards the front of the machine.

Another object is to provide an improved machine which will produce upholstery having tapered pleats. In this form of apparatus, means 25 are provided for moving the rear end portions of the conveyor-members, to vary the degree of convergence, as the fabric is advanced to the sewing mechanisms.

In the use of the improved machine as preferably constructed, a cover-fabric, a lining-fabric, and strips of batting are fed through the machine, the cover-fabric being the lower fabric in the upholstery-forming operation; the lining-fabric has formed therein upstanding seam-portions; 35 the cover-fabric has formed therein upstanding seam-portions and intervening depressed pleats, or pipes, the seam-ridges of the cover-fabric becoming nested within the seam-ridges of the lining-fabric; the strips of cotton batting, or the like, are drawn through with the fabrics and fill the pipes; and the upstanding, nested seam-ridges of the lining-fabric and cover-fabric are sewed by 40 means of sewing mechanisms mounted on the cross-beam above the path of the materials, each sewing mechanism carrying a sewing needle and a looper needle.

The work is fed continuously through the machine. The lining is a continuous fabric; the cotton batts are continuous strips; and the cover-fabric may be either a continuous fabric or pre-cut covers. In either case, a continuous piece of pleated upholstery may be produced which may be cut into suitable lengths for use in upholstery seats, backs, or the like.

55 Provision is made for breaking or severing of

batting strips at suitable intervals corresponding with the spaces between cushions. That is, the feed of the batting strips is periodically arrested and the strips broken or severed, so that the strips will not extend across the spaces between 5 cushions.

The sewing mechanisms and certain other mechanisms which are disposed above the path of the work, preferably are mounted on a vertically adjustable cross-head. This cross-head is 10 equipped with pairs of lining-creasing members and with a forming-roll provided with circumferential grooves adapted to accommodate the seam-ridges, and the bed of the machine is equipped with forwardly-converging endless 15 toothed ridge-chains upon which the cover-fabric is carried through the machine, the front portions of these ridge-chains working through grooves of the forming roll. The seam-ridges of the fabrics are brought into nested relation when the materials pass between the ridge-chains and the forming-roll. The convergence of the ridge-chains enables them to gather the cover-fabric and in conjunction with superposed shoes to 20 perform the seam-ridges and intervening pleats of 25 the cover-fabric.

When it is desired to form upholstery cushions with tapered pleats, the rear end-portions of the ridge-chains are moved laterally so as to vary the pleat width as it progresses through the machine; 30 and the lining-fabric is drawn between fixed ridge-bars and presser-members which are adapted to vary the space between the seam-portions by pressing the fabric between bars to a progressively increasing degree so that the space 35 between the seam-portions will correspond with the spacing of the seam-portions in the cover-fabric.

The invention is illustrated in a preferred embodiment in the accompanying drawings, in 40 which—

Fig. 1 is a broken side elevational view of a machine embodying the invention; Fig. 2, a broken sectional plan of the bed of the machine; Fig. 3, a broken longitudinal sectional view of the machine taken as indicated at line 3 of Fig. 2; Fig. 4, a broken elevational view of the rear portion of the machine showing the piece-placing mechanism; Fig. 5, a broken detail elevational view of the cam mechanism for operating the 45 piece-placing mechanism; Fig. 6, a broken sectional detail view, taken as indicated at line 6 of Fig. 4; Fig. 7, an enlarged broken longitudinal sectional view, taken as indicated at line 7 of Fig. 2; Fig. 8, a broken detail sectional view of the 50 55

fabric-supporting rock-plate; Fig. 9, a broken sectional view taken as indicated at line 9 of Fig. 3; Fig. 10, an enlarged broken sectional view of the front sprocket wheel, taken as indicated at line 10 of Fig. 3; Fig. 11, an enlarged plan view of one of the rear sprocket wheel supporting members; Fig. 12, an enlarged broken sectional view showing one of the sewing mechanisms, taken as indicated at line 12 of Fig. 3; Fig. 13, a broken plan view of a completed strip of upholstery; Fig. 14, a broken elevational view of a modified form of the invention showing the mechanism for forming the lining-fabric used in connection with a cover-fabric having tapered pleats; Fig. 14a, a broken detail sectional view showing one of the presser-members acting upon a lining-fabric supported by longitudinal ridge-bars; Fig. 15, a broken longitudinal sectional view taken as indicated at line 15 of Fig. 16; Fig. 16, a broken plan view of the bed of the modified machine, showing the movable converging ridge-chains; Fig. 17, a broken sectional view taken as indicated at line 17 of Fig. 16; Fig. 18, a broken plan view of a strip of continuous upholstered cushions having tapered pleats; Fig. 19, a diagrammatic broken elevational view showing mechanism for gathering the lining-fabric to be used in connection with cover-fabrics having tapered pleats; Fig. 20, a diagrammatic plan view showing the relation between the vertically disposed ridge-bars and presser-members; Fig. 21, a broken detail elevation showing a lining-fabric tensioning means; Fig. 22, a broken detail elevational view showing the inner rolls of the fabric-tensioning device; and Fig. 23, a sectional view taken as indicated at line 23 of Fig. 21.

In the preferred embodiment illustrated, A designates the main frame of a machine which is equipped near its front end with a vertically movable cross-head A' and which also has a rearward extension A² which constitutes a portion of the bed of the machine; B, a lower feed-roll journaled in the front end of the frame and constituting the main drive-shaft of the machine; B' a companion shaft journaled in the frame some distance back of the roll B; B², a chain connecting the shafts mentioned; B³, an upper feed-roll co-acting with the roll B; C, a sprocket drive shaft disposed about midway between the shafts B and B'; C', a series of rear sprocket-wheel shafts around which endless ridge-chains C² turn; and D, (Fig. 3), a series of fabric-forming shoes superposed above the ridge-chains C²; E, a forming-roll journaled in the cross-head A' and vertically movable therewith; F, (Fig. 2) a sprocket-chain connecting the roll B and the shaft C; G, (Fig. 2) gear-means through which the vertically movable forming-roll E is driven from the continuously rotating shaft C; H, (Fig. 3) a continuously rotating batt-feeding roll journaled in the brackets H' carried by the cross-head A'; I, a continuously rotating batt-deflecting roll journaled in the brackets H'; J, a batt-feeding roll journaled on members carried by the main frame, said roll being adapted to be periodically arrested to affect severance or breakage of the batts; K, a series of tubular batt-guides through which batting-strips K' are fed; L, (Fig. 1) a support for a roll of lining-material L'; M, a series of pairs of lining-creasing members supported on shafts or cross bars M' which connect brackets M² carried by the cross-head A'; N, a series of sewing mechanisms mounted

on the cross-head A'; O, a thread supporting rack mounted above the front portion of the machine; P, a piece-placing mechanism adapted to feed pre-cut fabrics seriatim to the fabric-ridge chains C²; and Q, a presser-device adapted to press the cover-fabrics into engagement with the fabric-ridge chains. 5

The frame A may be of any suitable construction. In the illustration given, a rearward extension A² is shown supported at its front end 10 on a pedestal 1 of the main frame, and at its rear end on legs 2.

A series of sprocket wheels 3 are keyed to the shaft C so as to be laterally adjustable thereon. The front chain-supporting members 4 are supported on cross members 5 and 6 of the main frame A (Fig. 3), and are laterally adjustable by means of bolts 7 which engage slots 6^a in the cross bar 6. These members support and house the front portion of the chains C³ and are open 20 at their upper side to permit the chains to engage the cover-fabric. The cross bar 6 is further provided with a rearwardly extending bracket 8 which pivotally supports the front end portion of the rear chain-supporting members 9, which are rigidly secured to sprocket supporting brackets 10 in which the shafts C' are journaled. The rearward extension of the bed A² is provided with a cross-bar 11 having a T-shaped slot 11^a which is engaged by a cap screw 11^b on 30 the supporting bracket 10 so that the latter may be adjustable thereon. The cap screw 11^b extends through a slot in the bracket 10 so that the ridge-chains C² may be tensioned by means of an adjusting screw 12 having a lock nut 12^a. The 35 bed A² is provided with a pair of longitudinal floor members 13 which extend from the cross bar 11 to the vicinity of the feed-rolls B and B³. These members serve to support the marginal portions of the cover-fabrics L' while being 40 gathered and advanced by the chains C².

The ridge-chains C² are of the usual sprocket-chain construction and are provided with a series of outwardly extending teeth, or fabric engaging pins 14. The construction of the chain 45 is such that it may be bent laterally to a limited degree as indicated in Fig. 2, without interfering with its operation.

The fabric-forming shoes D are supported by the cross-bar 15 of the frame which is provided 50 with a T-shaped slot 15^a which is engaged by cap screws 16 so that the shoes may be adjusted laterally thereon. The rear portion of the shoes is turned upwardly as indicated at 17. The flange portions 17^a are shaped to closely confine 55 the advancing cover-fabric about the front housing member 4, as indicated in Fig. 9. The shoes extend forwardly to a position beneath the forming-roll E.

As indicated in Fig. 10, one side of the front portion of the housing members 4 is cut away and stripper-blades 20, which are adjustably secured to the frame A by means of bolts 21, extend alongside of the ridge-chains C². The top edge-portion of the blades 20 is inclined upwardly as indicated at 20^a, so that the advancing fabrics are lifted upwardly from engagement with the pins 14 and directed to the sewing mechanisms N. 60

The forming-roll E may be of any desired construction and is driven from the shaft C by means of a gear housing G which permits it to move vertically with the cross-head A'. Ordinarily, it comprises a shaft 22 equipped with 70 75

adjustable grooved collars 23 through which the seam-portions of the fabric are carried by the pins 14.

A detailed description of the operation of the 5 batt-feeding mechanism, the lining-creasers, sewing mechanisms, lining-roll support, and thread supporting rack will be found in my Patent No. 1,915,329.

Referring to Fig. 13, it will be understood that 10 the finished strip of upholstery cushions comprises the continuous lining-fabric L', a series of cover-fabrics L², sewed to the lining-fabric and provided with pleats stuffed with batting designated K'. The batt-feeding roll J, described 15 in my application above, is adapted to periodically arrest and effect severance or breakage of the batts so that spaces 25 between the ends of the cover-fabrics L² will not be bridged by the strips of batting, and such a waste of material 20 is avoided.

Referring to Figs. 7 and 8, it will be understood that the cover-fabrics L² are not fed directly into engagement with the pins 14, but are advanced to a position above the shafts C' and the 25 advance marginal edge portion is held in that position by means of a series of yielding plates 26 which are adjustably secured to a rock shaft 27 by means of bolts 28^a. The rock shaft 27 is provided with an arm 27^a which is connected to a spring 28 to releasably urge the plate 26 to its upper position. The plate 26 is provided with slots 26^b which permit the plates to be pressed 30 down around the rear sprocket wheels 3 and permit the pins 14 to impinge the cover L². The swing of the plates 26 may be regulated by 35 a bracket 29 attached to the bed A² and provided with adjusting bolts 30 and 31 which are in the path of the rock-arm 27^a. The bolts may be provided with suitable lock-nuts 30^a and 31^a, respectively.

A table-member or platform designated A³ is mounted on the rear portion of the bed A² and the cover-fabrics L² are positioned, individually, 45 on this table from a stack of covers (not shown) by hand.

The bed A² is provided with brackets 32 which support tubular slide members 33 upon which the piece-placing mechanism P is reciprocably mounted. The piece-placing mechanism is described in my co-pending application Serial No. 572,691 filed November 12, 1931. It might be stated, however, that the mechanism includes a pair of goose-neck base members 34 slidably mounted on the hollow shafts 33, and provided with rearward extensions 34^a in which is journaled a rock-shaft 35.

Secured to the rock-shaft 35, are pusher arms 35^a whose lower front extremities are equipped with yielding friction-members 35^b. The members 35^b are adapted to frictionally engage the front corner-portions of the cover-fabric and slide it forwardly with its front marginal edge portion over the plates 26. The rock-shaft 35 is further provided with an actuating arm 35^c which is linked to an actuating arm 36^a of a companion rock-shaft 36 journaled on the upper front portion of the goose-neck 34. It will be understood, referring to Fig. 4, that the friction-members 35^b will be raised through the action of a downwardly projecting arm 36^b, of the rock-shaft 36, engaging a strike 37 which is mounted on the bed A². The arm 36^b is provided with a projection 36^c adapted to be engaged by a trigger-member 38 which is pivoted to the goose-neck slide member 34. The

trigger-member serves to hold the arm 36^b during the rearward movement of the piece-placing mechanism. The bed A² is further provided with a trigger-release member 39 having a spring-held tip 39^a which permits the member 38 to pass rearwardly but trips it on its forward movement so that the arm 36^b is released and the presser-members 35^b are lowered into contact with the cover fabric L².

The piece-placing mechanism is reciprocated by 10 means of a sprocket chain 40 which extends through the tubular members 33, around the rear sprocket members 40^a and front sprocket wheels 40^b which are mounted on a transversely extending drive shaft 41 journaled in the bed A². The 15 end portions of the chains 40 are attached to downward extensions 34^b of the goose-neck slide-members 34 so that the movement thereof is controlled by the rotation of the shaft 41. One end of the shaft 41 is equipped with a bevel gear 42 20 which meshes with a companion bevel gear member 43 which is journaled in the bracket 43^a mounted on the bed A². The lower portion of the gear member 43 is equipped with a universal joint 44 so that a depending friction wheel shaft 45 may 25 be swung forwardly and rearwardly by means of a rock-member 46 which is pivoted to the frame A². The rock-member 46 is actuated by a pitman 47 pivoted at 47^a to a rock-member 48 which is provided with a roller 48^a and is pivoted to the frame A at 48^b. A cam 49 controls the movement 30 of the rock-member 48 and is mounted on a shaft 50 which is driven by the shaft B through a train of gears (not shown).

A reversing movement of the piece-placing 35 mechanism is accomplished by alternate engagement of the friction wheel 45 with friction wheels 51 and 52 mounted on the shaft 53 which is journaled in brackets 53^a on the frame A². The shaft 53 is rotated continuously from the drive shaft 54 40 by means of a sprocket chain connection 54^a.

The mechanism Q is provided to impinge the pre-cut fabric L² on the pins 14 after the fabric has been advanced onto the plates 26. Referring to Figs. 4 and 7, it will be seen that a bracket 55 carried by the frame A² supports a presser roll 56 and a rock-shaft 57. The rock-shaft 57 is provided with an actuating arm 57^a and roll-supporting arms 57^b in which is journaled a presser roll 58. The presser rolls 56 and 58 preferably are provided with stiff bristles 59 which are adapted to press the fabric into engagement with the pins. The actuating arm 57^a is connected to a pitman 60 which, in turn, is pivoted to a trigger-member 61 pivoted at 61^a to a bracket 62 carried by the bed A². A spring 60^a is connected to the pitman 60 so as to urge the roll 58 into fabric engaging position. In order to raise the roll 58 while the piece-placing mechanism is advancing the fabric 65 onto the plates 26, the trigger-member 61 is provided with a pivoted finger 61^b which extends into the path of the rock-shaft 35. A spring 61^c urges the finger 61^b forwardly against a stop 61^d on the trigger-member so that the rearward movement of the piece-placing mechanism will not affect the trigger-member 61. It will be understood that the forward movement of the piece-placing mechanism will cause the roll 58 to be raised slightly as the cover-fabric is advanced 70 onto the plates 26 and the roll will then be permitted to swing down, depress the plate 61 and impinge the fabric onto the pins 14. The roll 56 further assists in pressing the fabric into engagement with the pins.

The operation of the machine may be described briefly as follows: The piece-placing mechanism travels to its extreme rearward position, the friction-members 35^b are lowered into engagement 5 with the pre-cut fabric and advance it until the front marginal portions extend over the plates 26, whereupon the roller 59 will descend and press the fabric into engagement with the continuously advancing pins 14; as the fabrics are advanced 10 by the chains C², they will be gathered into progressively increasing pleat-fulnesses due to the convergence of the chains towards the front of the machine; upon reaching the forming-shoes D, the elevated seam-portions of the fabric will be 15 formed into U-form seam-ridges around the housing members 4; at the same time the lining-fabric L' has been advancing down through the lining-creasing members M beneath the forming-roll E where said lining-fabric will also be engaged 20 by the pins 14; also the cotton batting strips K' will be introduced between the fabrics into the pleat-fulnesses; the stuffed fabrics will then advance under the forming-roll E, be stripped from the pins by the stripper member 25 20 and fed into the shoe of the sewing mechanisms where the transverse stitching will be done, as indicated in Fig. 12; the upholstery is then advanced and withdrawn from the machine by means of the rolls B and B³.

30 In the modified form, R designates the main frame, having a vertically movable cross-head R' and rearward extension R²; S, a forming-roll journaled in the front portion of the main frame; T, a series of tubular batt-guides through which 35 strips of batting T' are fed; U, pre-cut cover-fabrics which are fed into engagement with a lining-fabric U'; V, piece-placing mechanism; and W, a device for pressing the pre-cut covers U into engagement with the conveyor members.

40 By modifying the mechanism as indicated in Figs. 14-23, the machine is adapted to form tapered pleats of the character as illustrated in Fig. 18. The machine is practically identical with the one described above with certain additions 45 which will now be explained.

As shown in Fig. 16, the rear chain-supporting members 74 are provided with rigidly connected supports 75 which are adapted to slide on the cross member 76 of the machine. It will be 50 understood that the chain-supporting members are pivotally mounted at their front ends on studs 74^a. Each of the supports 75 (with the exception of the center support if an odd number are used) is equipped with a pivotally connected 55 rack-bar 77 which extends transversely to one side of the machine where each rack is held in engagement with an individual gear 77^a by means of springs 77^b. The gears are all of different diameters and are fixedly mounted on a shaft 78 journaled in brackets 78^a on the bed of the machine. Due to the difference in the diameter of 60 the gears, it will be understood that when the shaft 78 is oscillated, the lateral movement of the members 75 will be varied depending upon the diameter of its actuating gear. Thus, the supporting members 75 which are near the center of the bed of the machine may be given a slight movement by employing a small diameter 65 gear while the supporting members nearer the edge portions of the bed will be given a progressively larger swing by employing gears with larger diameters. The rear end portion of the shafts 78 are equipped with bevel gears 78^b which are 70 engaged by bevel gears 79 fixedly mounted on a 75

transversely extending shaft 80 which is journaled in the bed R² of the machine. The shaft 80 is provided with a rock-arm 80^a which is urged forwardly by means of a spring 80^b. One end portion of the shaft is further provided with an actuating arm 80^c having pivotal connections with a pitman 81 connected to a rock-arm 82 which is pivoted to the main frame at 82^a. The opposite end of the rock-arm 82 has a pivotal connection with a pitman 83 which, in turn, is 10 pivotally connected at 83^a with a cam engaging rock-arm 84 pivoted to the main frame of the machine at 84^a. A cam shaft 85 is continuously rotated by a train of gears (not shown) and is provided with a cam 86 which engages and actuates the rocker-arm 84. 15

In order to provide the lining-fabric U' with seam-portions and intervening pleat-spaces, tapering longitudinally and conforming to the pleat-fulnesses in the cover-fabrics U which it 20 meets beneath the forming-roll S, a special mechanism is provided which is carried by the cross head R' and is illustrated, diagrammatically, in Figs. 14 and 19-23.

As shown in Fig. 14, the lining-fabric passes 25 over a guide-roll 90 carried by an upper frame member 91, and over spaced ridge bars 92, whose lower ends are fixedly mounted on the main frame R and the upper ends supported on a rod 92^a attached to the frame 91. The lining-creasing 30 mechanism has a frame 93 whose lower end 93^a projects into a slot 95 in the cross-head R' and its upper end is attached to the cross-head by means of clamps 96 and bolts 96^a. A rock-shaft 97 is journaled in the frame 93 and is provided with a series of laterally adjustable rock-arms 97^a equipped at their lower ends with presser-rollers 97^b. The arms 97^a are laterally adjustable on the shaft 97 so that the presser-rollers will engage the lining fabric U' about mid-way between each pair of longitudinal ridge-bars 92. 35

It will be understood that the presser-rollers are made to swing between the bars 92 and the amount of swing will determine the pleat-spacing between the seam-portions when the lining-fabric comes into engagement with the pre-cut covers beneath the forming-roll designated S. The shaft 97 is provided with an operating rock-arm 98 provided with a slot 98^a to which is adjustably connected a push-rod 99 40 whose lower end makes a pin-and-slot lost motion connection with a push rod 100 pivoted at 100^a to a rock-arm 101 which is pivoted to the main frame of the machine with the rock-arm 84 at 84^a. The rock-arm 101 rides on a cam 102 which is fixedly mounted on the continuously rotating cam-shaft 85. A spring 98^b is connected to the push-rod 99 so as to urge the member downwardly. It will be understood that as the cam shaft 85 rotates counter-clockwise, the arm 101 will be raised gradually and will cause the rollers 97^b to press the lining-fabric between the ridge bars 92 a progressively increasing amount which will provide spaces between the seam-portions to correspond with the tapering pleats in the cover-fabrics. 45

After the lining-fabric has been depressed to meet the maximum requirement, the cam permits the arm 101 to drop down suddenly and swing the rollers 97^b forwardly. When this occurs, it is necessary to stretch the lining-fabric laterally and this stretching is accomplished by means of temple-members 103 (shown in Figs. 21-23) which constantly engage the marginal edge portions of the fabric. The temple-members are standard 50 55 60 65 70 75

articles of manufacture which are obtainable on the market, and no invention is claimed therein. They are each provided with a pair of toothed rollers within a housing, which is open at both sides and one end, so that a fabric may be drawn through from one side to the other without interference, but lateral movement of the fabric within the housing is prevented. As illustrated in the drawings they comprise a housing 103^a in which are journaled rollers 103^b which are provided with a series of outwardly projecting fabric-engaging pin points 103^c. The temple-members are provided with inwardly projecting lips 103^d which guide the fabric into engagement with the pins. The temple-members 103 are attached to arms 104, by means of bolts 104^a, and arms 104 are pivotally connected at 104^b to a cross shaft 105 carried by the frame 91.

In order to swing the temple-members laterally at the proper time, they are each provided with a yoke 105^a through which projects a transversely slideable rod 106 having a pair of fixed collars 106^a which engage the yoke. The rods are supported by brackets 106^b mounted on the frame 93. The slide rods have pivotal connections 106^c with pitmans 107 which are connected to opposite ends of a rock-member 108 which is pivoted at 108^a to the frame member 93. The rock-member 108 is provided with a slot 108^b to which is adjustably connected a push-rod 109 extending laterally and making a pivotal connection at 109^a with a crank 110 pivoted at 110^a to the frame 93. The crank 110 is provided with an arm 110^b which extends into the path of the push-rod 100. The upper end portion of the rod 100 is provided with a slot 100^b which is engaged by a pin 111, carried by a bracket 112 on the cross-head R'. A spring 109^b is connected to the push-rod 109 so as to yieldingly urge the temple-members outwardly.

It will be understood, therefore, that the rotation of the cam shaft 85, counter-clockwise, will cause the temple-members to swing inwardly, against the action of the spring 109^b, while the rollers 97^b are being thrust backwardly between the bars 92, and, accordingly, the fabric is always kept in a smooth and taut condition.

The operation of the machine equipped with the additional mechanism shown in Figs. 14-23, is the same as the operation of the machine described above, except that the pleats in the cover-fabric are tapered, due to the continuously changing distance between the ends of the conveyor members which initially impinge the cover-fabrics, and the spacing between the seam-portions of the lining-fabric is also progressively increased by the action of rollers 97^b which move in timed relation to the cover-fabric forming mechanism. It will be understood, that the cover-fabric will not be torn or stretched by the movement of the end portions of the conveyors for the latter are disposed in converging relation and the fabric is being advanced forwardly at the same time the conveyors are spread apart.

Obviously, the mechanism is adapted to form tapered pleats in continuous cover-fabrics as well as with pre-cut covers. When continuous fabrics are used, the piece-placing mechanism may be omitted.

If desired, the pleats may be arranged to taper alternately from front to rear and then from rear to front by changing the shape of cams 86 and 102. If it is desired to do this with pre-cut cover-fabrics, alternate covers should be reversed, end for end, before being delivered to the piece-placing mechanism.

The foregoing detailed description is given for clearness of understanding only, and no unnecessary limitations should be understood therefrom, but the appended claims should be construed as broadly as permissible in view of the prior art. 5

What I regard as new, and desire to secure by Letters Patent, is:

1. In a machine of the character set forth: a bed over which a fabric may pass; a forming-device disposed over said bed having spaces through which seam-portions may pass; means comprising forwardly-convergent spaced pleater-conveyors in said bed operative to form and carry raised seam-portions in converging lines forwardly beneath and beyond said forming-device; means for bringing a second fabric beneath said forming-device and into contact with the seam-portions of the first fabric; and sewing-mechanisms in advance of said forming-device operative to sew said fabrics together at said seam-portions. 10

2. In a machine of the character set forth: a main frame having a bed equipped with means for gathering and forming a cover-fabric into raised seam-portions and intervening depressed pleat-fullnesses, comprising a series of endless convergent spaced conveyor-members adapted to engage simultaneously each of the seam-portions of said fabrics at their initially encountered ends and carry the engaged portions along convergent 25 lines, thereby effecting pleating of the fabric substantially perpendicular to the direction of travel of said fabrics, said conveyor-members having their initially encountered ends substantially in transverse alignment. 35

3. In a machine of the character set forth: a main frame provided with a bed and means for gathering and forming a cover-fabric into raised seam-portions and intervening depressed pleat-fullnesses, said means comprising travelling seam-portion-supporting ridge-chains converging towards the front of the machine, each of said chains being provided with impaling pins adapted to positively engage the fabric. 40

4. In a machine of the character set forth: a main frame provided with a bed; a series of seam-portion-supporting ridge-chains mounted on said bed, said ridge-chains being equipped with fabric-engaging pins; holding means adapted to hold initially the advance-margin of pre-cut fabric 50 above said ridge-chains; and presser-means adapted to depress said holding-means and to press the fabric into engagement with the pins. 55

5. In a machine of the character set forth: a main frame provided with a bed; a series of ridge-chains mounted on said bed, said ridge-chains being equipped with fabric-engaging pins; means adapted to hold initially the advance margin of a fabric above said ridge-chains; mechanism for placing a pre-cut fabric on the fabric-holding 60 means; and presser-means adapted to press the fabric into engagement with said pins comprising a rock-shaft having arms, a presser-roll journaled in said arms, and means actuated by the fabric-placing mechanism for lifting said presser-roll 65 from engagement with said fabric. 65

6. Mechanism as specified in claim 5, in which the means for rocking the presser-roll comprises a rock-arm mounted on the rock-shaft, an actuating arm pivoted to the bed of the machine, a link 70 connecting the rock-arm to said actuating-arm, and a spring-held trigger member on said actuating arm in the path of the piece-placing mechanism serving to move said arm during forward working stroke of said piece-placing mechanism. 75

7. In a machine of the character set forth: a main frame provided with a bed; means for gathering and forming a cover-fabric into raised seam-portions and intervening pleat-fullnesses comprising a series of endless forwardly convergent spaced conveyor-members adapted to engage the seam-portions of said fabric at its initially encountered ends and carry the engaged portions along convergent lines, thereby effecting pleating of the fabric; and means for changing the angle of convergence of the conveyor-members as they advance said fabric.
8. In a machine of the character set forth: a main frame provided with a bed; means for gathering and forming a cover-fabric into raised seam-portions and intervening pleat-fullnesses, said means comprising travelling ridge-chains converging towards the front of the machine, each of said chains being provided with pins adapted to engage the fabric and secure the same on said chains; and means for changing the degree of convergence between said chains while they are advancing the fabric.
9. In a machine of the character set forth: a main frame provided with a bed; travelling ridge-chains supported on said bed and converging towards the front of the machine, the rear portion of said chains being slidable transversely on said bed; and means for shifting the rear portion of said chains to change the angle of convergence between the chains in timed relation to the travel thereof.
10. In a machine of the character set forth: a main frame provided with a bed; means for advancing a pre-cut fabric and forming therein raised substantially uniform seam-portions and intervening longitudinally graduated-depth pleat-fullnesses; means for forming a lining-fabric into seam-portions with intervening fullnesses corresponding to the graduated fullnesses of the pre-cut fabrics; and mechanism for sewing said fabrics together at their seam-portions.
11. A machine as specified in claim 10, in which the means for forming the lining-fabric comprises a series of spaced ridge-bars, and power-actuated means for pressing the lining-fabric between said bars to a progressively changing degree to provide the required graduated fullnesses.
12. Mechanism as specified in claim 10, in which the means for forming the lining-fabric comprises a series of ridge-bars, a rock-shaft having a series of arms provided with presser-rolls adapted to press the lining-fabric between said bars, and means for rocking said presser-rolls into the spaces between the ridge-bars in timed relation to the movement of the pre-cut fabrics.
13. In a machine of the character set forth: a bed over which a cover-fabric may pass; a forming-device disposed over said bed having spaces through which seam-portions may pass; forwardly-convergent spaced pleater-conveyors in said bed operative to carry the seam-portions in converging lines forwardly beneath said forming-device; means for moving transversely the rear portions of said pleater-conveyors as they advance the fabric so as to form graduated-depth pleat-fullnesses; means for bringing a second fabric beneath said forming device and into contact with the seam-portions of the first fabric; and sewing mechanism in advance of said forming-device operative to sew said fabrics together.
14. Mechanism as set forth in claim 13, in which means are provided for pre-forming the second fabric into seam-portions and intervening graduated-depth pleat-fullnesses in timed relation to the advance of the cover-fabric.
15. In a machine of the character set forth: a bed over which a fabric may pass; a forming device disposed over said bed having spaces through which seam-portions of the fabric may pass; means for advancing said fabric to the forming device and for forming substantially uniform seam-portions with intervening graduated-depth pleat-fullnesses; means for forming a second fabric into substantially uniform seam-portions and graduated-depth fullnesses and guiding the seam-portions beneath said forming device into contact with the seam-portions of the first fabric, comprising spaced ridge-bars disposed above said bed, a rock-shaft having a series of arms adapted to press said lining-fabric between said bars, and means for progressively moving said arms in timed relation to the movement of the first fabric to provide corresponding seam-portions and tapered pleat spaces; and sewing mechanisms in advance of said forming device to sew the fabrics together at their seam-portions.
16. In a machine of the character set forth: a main frame provided with a bed; a plurality of endless spaced conveyor-members equipped with fabric-impaling means; and mechanism adapted to vary the angles between said conveyor-members during the feeding of the fabric by said conveyor-members.
17. A machine as specified in claim 16, in which said conveyor-members comprise endless chains equipped with fabric-impaling members.
18. A machine as specified in claim 17 in which said conveyor-members comprise endless chains equipped with impaling pins, and means for maintaining the front portions of said chains in substantial parallelism and means for varying the angles between the rear portions of said chains.
19. In a machine of the character set forth: a main frame provided with a bed; and means for gathering and forming a cover-fabric into raised seam-portions and intervening pleat-fullnesses, comprising a plurality of endless chains spaced with relation to each other and equipped with fabric-impaling members; means for driving said chains; and means for automatically varying the spaced relation of said chains during the feeding of fabric by said chains.
20. In a machine of the character set forth: a main frame provided with a bed; and means for gathering and forming a cover-fabric into raised seam-portions and intervening pleat-fullnesses, comprising a series of spaced chain-housings having substantially parallel front sections and rearwardly diverging rear sections, endless chains having fabric-impaling means projecting above said chain-housings, and adapted to engage the seam-portions of said cover-fabrics, and means for driving said chains.
21. A machine as specified in claim 20, in combination with pre-cut fabric piece-placing mechanism operative to advance the front margin of the fabric-piece to a position above the rear portions of said chains, and a presser device periodically operative to press the fabric-piece onto the impaling devices at the rear portions of said chains.
22. In an upholstery making machine: a frame having a bed equipped with spaced longitudinal seam-portion-forming pleater-chains provided with fabric-impaling means; piece-placing mechanism operative to advance pre-cut fabric-pieces, seriatim, to bring the front margin of

the fabric-piece over the rear portions of the pleater-chains; a presser device for moving the fabric-pieces into engagement with the pleater-chains; and means for periodically actuating said 5 presser device.

23. A machine as specified in claim 22, in which said presser device is capable of being raised and lowered and is actuated by said piece-placing mechanism.

10 24. In an upholstery forming machine: a frame having a bed equipped with spaced longitudinal pleater-chains provided with seam-engaging members; and fabric piece-placing mechanism comprising a platform adapted to support a fabric-piece, pusher-arms adapted to engage the fabric supported on said platform; and means for giving to said push-arms a traverse, the front end of such traverse terminating above the rear portions of said pleater-chains.

20 25. Mechanism as specified in claim 24, characterized by depressible fabric-supporting means associated with the front portion of said platform, and characterized further by a device for depressing the advance margin of the fabric-piece 25 and said depressible means to cause the fabric to engage the impaling members of the pleater-chains.

30 26. In the manufacture of upholstery, the steps which comprise: positively engaging a fabric at a plurality of transversely spaced points corresponding with seam-portions and carrying said engaged points forwardly and into closer relation to provide the fabric with such seam-portions and intervening pleat-fullnesses; bringing a second fabric into engagement with the first fabric while said points of the first fabric remain positively engaged; and sewing said fabrics together at their seam-portions as they are advanced.

40 27. In the manufacture of upholstery, the steps which comprise: impaling a fabric progressively at a plurality of transversely spaced points corresponding with seam-portions and carrying the impaled points forwardly while lessening the transverse spaces between them, thus providing the fabric with seam-portions and intervening pleat-fullnesses; bringing a second fabric into engagement with the first fabric while said points of said first fabric remain impaled; and sewing the fabrics together at their seam-portions as the 50 fabrics are advanced.

55 28. In the manufacture of upholstery, the steps which comprise: progressively impaling a fabric-piece at transversely spaced points corresponding with seam-portions and carrying the impaled points forwardly and into closer relation to provide seam-portions and intervening pleat-fullnesses; bringing a second fabric into engagement with the first fabric and into impaled relation therewith; stripping the seam-portions of the fabrics from the impaling devices; and sewing the fabrics together at their seam-portions as the fabrics are advanced over the stripping devices.

65 29. In the manufacture of upholstery, the steps which comprise: moving a plurality of series of impaling members along convergent lines; bringing a fabric into engagement with successive impaling members at their widely separated points and carrying the impaled points of the several series forwardly and into closer transverse relation and thus forming seam-portions and intervening pleat-fullnesses, bringing a second fabric into engagement with the first fabric while it remains impaled; and stripping the fabrics from

the impaling members and sewing them together as the fabrics are advanced.

30. In the manufacture of upholstery, the steps which comprise: positively engaging a fabric at transversely spaced points corresponding with 5 seam-portions and carrying said engaged points forwardly and into closer relation to provide seam-portions and intervening pleat-fullnesses; bringing a second fabric into engagement with the first fabric while said points of the first fabric 10 are still positively engaged; introducing batting strips into the pleat-fullnesses between the fabrics; and sewing together the seam-portions of the fabrics as the fabrics are advanced.

31. In the manufacture of upholstery, the 15 method of forming tapered pleats, which comprises: positively engaging a fabric at transversely spaced points corresponding with seam-portions and carrying said engaged points forwardly along converging lines and varying the convergence of said lines, thus providing such seam-portions and intervening graduated-depth pleat fullnesses, bringing the second fabric into engagement with the first fabric while said points of the first fabric are still positively engaged; and sewing 20 the seam-portions of the fabrics together as the fabrics are advanced.

32. The method of manufacturing upholstery with tapered-pleats which comprise: positively 30 engaging a fabric at transversely spaced points corresponding with seam-portions and carrying said engaged points forwardly and into closer relation to provide such seam-portions and intervening pleat-fullnesses, the distance between the 35 engaged points at the initial engagement of the fabric being varied; bringing a second fabric into engagement with the first fabric; and sewing the fabrics together at their seam-portions as the fabrics are advanced.

33. The process stated in claim 32, characterized by increasing the distance between the initial points of engagement progressively while the fabric is being carried forwardly.

34. In the manufacture of upholstery having tapered-pleats, the steps which comprise: moving 45 a plurality of series of fabric impaling members along spaced convergent lines having a varying convergence; and causing successive portions of a fabric to be engaged by said members at points corresponding with seam-portions and effecting progressive variation of the spacing between the points where the initial engagement occurs, the fabric being then carried forward by said members and formed into such seam-portions and intervening graduated-depth pleat-fullnesses. 55

35. A method of manufacturing upholstery having tapered pleats, which comprises: feeding a continuous lining-fabric; feeding, seriatim, pre-cut cover-fabrics and forming in the pre-cut 60 cover-fabric substantially uniformly spaced seam-portions and intervening pleat-fullnesses of progressively changing depth; and bringing the formed cover-fabrics, in succession, into contact with the lining-fabric and sewing the seam-portions of the fabrics together. 65

36. In a machine of the character set forth: a bed over which pre-cut covers may pass; a driven series of forwardly convergent spaced ridge-chains mounted in said bed, each chain having a 70 series of spaced impaling pins serving to pierce and impale the seam-portions of superposed pre-cut covers as they are fed in succession to the rear portions of said chains; and mechanism serving to feed in succession pre-cut covers forwardly and 75

cause their seam-portions to be progressively impaled on the pins at the rear portions of said ridge-chains, whereby the successive portions of the several seam-portions will be carried forwardly and brought into closer relation with each other and pleat-fullnesses will be formed between the seam-portions.

37. Mechanism as specified in claim 36, combined with means for bringing a continuous lining-fabric into contact with the seam-portions of the successive pre-cut covers, and sewing-mechanisms operative to sew together the seam-portions of said covers and said lining. 5

ALLISTER S. MITCHELL.
